POSITION REGULATED GUN MOUNT

Clinton R. Hanna, Pittsburgh, and Lawrence B. Lynn, Wilkinsburg, Pa., assignors to Westinghouse Electric Corporation, East Pittsburgh, Pa., a corporation of Pennsylvania

Application February 10, 1942, Serial No. 430,200

5 Claims. (Cl. 89—41)

Our invention relates to a position regulator, particularly one including a gyro stabilizer for maintaining an element in a predetermined but adjustable position.

An object of our invention is to provide a means for remotely locating a gyro stabilizer from the element which it controls when necessitated by space limitations such as in an army tank.

A more specific object of our invention is to provide, in a gun mounting assembly in a tank or other similar frame structure, a parallelogram linkage means so connecting the gyro stabilizer and the gun which it controls, that although remotely situated from the gun and pivoted on some fixed axis, the gyro stabilizer will be acted upon in direct ratio to movements of said gun.

Another specific object of our invention is to provide in a gun mount, a manually operated elevating mechanism for the gun with a flexible driving means connecting the elevating means to the gyro stabilizer in such a fashion that the gyro stabilizer may be operated by the hand wheel of the elevating means and furthermore, by said flexible driving means, eliminate the necessity of disconnecting the gyro stabilizer from said elevating mechanism during manual adjustment of the gun.

Further objects and advantages will become more apparent from a study of the following specification when considered in conjunction with the accompanying drawings, in which:

Figure 1 is a perspective view of a gun control assembly embodying the principles of our invention and installed within a tank;

Fig. 2 is an enlarged view partly in section showing the parallelogram linkage and flexible driving means included in Fig. 1;

Fig. 3 is an enlarged perspective view of the anticipating gyro of the gyro stabilizer assembly included in Fig. 1;

Fig. 4 is an enlarged vertical section of the bearing mounting of the anticipating gyro taken along a plane defined by the x and y axes as viewed from the left;

Fig. 5 is a schematic showing of the position regulating control system embodied in Fig. 1;

Fig. 6 is a graph of the velocity curve plotted against the displacement curve of the gyroscope;

Fig. 7 is a fragmentary elevation, with parts shown in section, as viewed from the breech end of the gun;

Fig. 8 is a detail view taken along line VIII—VIII of Fig. 7;

Fig. 9 is a sectional view taken along line IX—IX of Fig. 2; and

Fig. 10 is an enlarged detail view of the gyro-
vertical shown in Fig. 1.

Referring to the drawings, we have, in Figures 1 and 2, a gun 1 mounted on a tank turret 3 together with a stabilizer assembly indicated generally at 5 for correcting for angular disturbances such as pitch or roll. Pitching is the rocking movement in a vertical plane in the direction of travel of the tank while rolling is movement about an axis in the direction of travel. The gun is pivotally mounted on trunnions 7 in the forward wall of the turret 3 which trunnions constitute an axis in a horizontal plane and at right angles to the gun-barrel axis giving freedom of gun movement in the elevation plane only. Azimuth movements of the gun may be achieved by rotating the gun turret or by laterally steering the tank, for example.

The gyro stabilizer, while forming no part of our invention per se, will be briefly described so that our invention may be more readily understood.

The gyro stabilizer assembly 5, described in more detail and claimed in a copending application of C. R. Hanna, Serial No. 366,877, filed November 23, 1940, entitled Gun stabilizers, includes as a component part, a "gyro vertical" so called because its axis of spin continuously tends to seek the vertical; thereby constituting a basis or reference for positioning a gun with respect to a distant target. The invention in said patent application is especially adapted to control the movements of a gun which is pivotally mounted on a tank so the gun, once aimed at a distant target, will be continuously trained on such target irrespective of disturbances or disturbing movements of the tank in the course of its travel. The numeral 9 denotes a support which must be so mounted as to partake of the pitching movements 40 of the gun and yet be adjustably mounted with respect to the gun. As elsewhere herein described, the controlling elements of the stabilizer are sensitive to change in angular position of the supporting element 9 and provision is made for 45 changing the angular relation of the supporting element and the gun to change the elevation of the latter. The controlling elements render the stabilizer effective to oppose change in angular position of the gun and therefore of the supporting element connected to move angularly therewith, with the result that the gun may be maintained aimed at the target within a narrow range of deviation. As a reference vertical is preferably employed in connection with the controlling elements, the latter assure of operation of the sta-

bilizer to restore the gun to aimed position in the event of departure therefrom because of a disturbance, the supporting element moving back with the gun until it and the controlling elements are restored to their former positions. Thus, with the angular position of the supporting element fixed by the biasing means or vertical reference, it is assured that the stabilizer will not only minimize deviation of the gun from aimed position but will restore the gun to that position with the supporting element in the position fixed by the reference vertical. Numeral 11 designates a bracket which is rigidly mounted on support 9 and which has pendulously mounted thereon in bearings a U-shaped pendulous member 13 in such position that it may move angularly about the upper x axis. It is apparent that if support 9 were to be gradually tilted in its own plane, pendulous member 13 would tend, at all times, to align itself with the center of the earth due to gravity. However, if such tilting movement were to become violent or if such support were to have vibratory movement of medium or high frequency, pendulous member 13 would become quite unstable and would tend to oscillate to such an extent that it could no longer be reliable as a means for indicating the direction of the earth's center. In order to stabilize the movement of pendulous member 13 a gyro vertical 15 is provided which is mounted in gimbals in bracket 11 in a position that it may pivot about the z and x axes. A motor denoted generally by M is located within the housing 17 and drives a flywheel 18 which constitutes a gyro wheel. Since such gyro wheel has a vertical axis of spin and since the motor and gyro assembly are pendulously mounted in gimbals, the gyro wheel axis will inherently and gradually seek a vertical or earth's center alignment position. If there were no friction in the universal gimbal mount and no other restraining force the gyro wheel axis would oscillate in a conical path indefinitely once its axis was tilted from the vertical. Friction at the gimbal bearings or any other resistance to such conical motion tends to precess the gyro wheel axis back to vertical in a spiral path. Constant friction, however, is highly undesirable because it prevents a complete return of the gyro wheel to its earth's center pointing position. A frictional damping means in the form of a flat strip or track member 21 having friction forming sides is rigidly fastened to the bottom of pendulous member 13. It is so positioned that it may be frictionally engaged by friction shoes projecting inwardly from the U bracket 23 supported on U piece 25 rigidly fastened to block 27 which clamps the gyro wheel in position and which carries it pivotally on bearings in its gimbals. The friction damper just described represents an improvement over that used in said copending application. In said copending application a channel was used in place of the flat strip 21. It was mounted in the same position in a manner that friction shoes mounted on a rod in place of bracket member 23 were positioned within the channel (instead of exterior thereof as shown in the present device) and frictionally engaged by its sides. Such channel member however had a tendency to warp, destroying the accuracy of the spacing of the sides of the channel and binding the friction shoes in the course of their travel within the channel. While warping may not be absent from the flat strip member 21 it is obvious that such distortion will not increase the thickness of said strip. Consequently while the friction shoes might not travel along a perfectly

straight track there will be no binding to restrict their travel.

Forces which would normally rotate or displace pendulous member 13 about its x axis are transmitted to the gyro vertical by the mechanical connection described above, attempting to displace it about its x axis. This displacement force instantly causes the gyro to precess at right angles to the applied force about its z axis. The precessional movement of the gyro through the above mechanical connection with pendulous member 13 exerts a reaction force opposite to the force of displacement, thereby, within the capacities of the gyro, substantially maintaining the pendulous member 13 in a vertical or earth's center pointing position. Precessional velocities of the gyro about its z axis move the friction shoes with respect to track 21. Sliding friction forces so developed are proportional to the precessional velocity. Displacement of the pendulous member 13 from the vertical is opposed by the gyro 15, torque applied by the pendulous member to the gyro causing the latter to precess about the precession or z axis and precessional velocity being accompanied by a gyroscopic or reaction torque which opposes the applied torque. As the gyroscopic or reaction torque is applied as a force normal to the friction surfaces of the track 21 and the shoes, friction force is developed and is effective as a couple about the precession axis to damp precessional oscillations in proportion to precessional velocity. As the precessional velocity approaches zero in response to displacement velocity approaching zero the sliding friction forces approach zero, consequently there is no error arising from this type of damping. The damping will be in wholly one plane as defined by the axes y and x and the gyro wheel axis will spiral inwardly in an unsymmetrical manner, that is somewhat of the form of a very flat elliptical spiral, with its larger axis located along the track 21. This dissymmetry is caused in part by the pendulousness of member 13 about the x axis. Since only one axis of accuracy is required, namely the x axis, the smaller stability about the z axis has no effect on the performance of the device. Sudden stopping or starting of the tank when the gun is pointed in a plane substantially parallel to the direction of travel will slightly displace the pendulous member 13 about its x axis but the stabilizing effect of the gyro vertical thereon confines such angular displacement within very small limits.

Rigidly supported from the underside of pendulous member 13, is a contact device denoted generally at 31 comprising a plurality of flexible metallic leaves 32 to the ends of which are secured contacts 33 preferably made of silver. Such contacts 33 are connected along spaced taps of a resistor 35. The contact device leaves are so adjusted that about half the total number of contacts is in the normally closed position while the other half are in the normally open position (see Fig. 5) so that actuating element 37 will progressively close the contacts on one side while opening those on the other thus simultaneously modifying the resistance in both the right and left-hand portions of resistor 35.

Assuming for the moment that actuating element 37 is rigidly secured with respect to support 9 then as support 9 is tilted clockwise within its own plane the gyro assembly remaining substantially vertical will cause the left-hand portion of contact device 31 to be progressively closed while the right-hand portion will be opened. Counter-

clockwise rotation of support 9 results in the reverse operation. At the beginning of disturbances of support 9 when the angular displacement θ (see Fig. 6) is small a relatively small number of contacts are closed. The angular velocity

$$\frac{d\theta}{dt}$$

of support 9, however, is at its maximum. It can be seen that a relatively large angular displacement is necessary before restoring forces will be of sufficient magnitude to check and then return support 9 to its normal or equilibrium position. When angular displacement returns to zero the angular velocity is maximum and the displacement stimulus has been removed. Since forces to check such movement are absent at zero displacement angular displacement counterclockwise from normal occurs.

From the above it is obvious that means responsive to displacement only are insufficient for most purposes, since it is accompanied by sluggishness and a significant amount of hunting which makes the system relatively unstable. A second gyroscope termed an "anticipating gyro," since it anticipates corrections and is responsive to the velocity of angular movement of support 9 within its own plane, that is, the velocity of the pitching disturbances. Such anticipating gyro performs an anti-hunting function, as will be apparent from the following description. Pivots and perpendicularly mounted to support 9 by means of a bearing assembly denoted generally at 38 (see also Figs. 3 and 4) is a substantially U-shaped bracket 41 within which is pivotally supported, on bearings, a block 43, in which block is clamped the motor housing 45 of the anticipating gyro, so that the center of gravity of the anticipating gyro assembly is in the intersection of the pivot axes of the block 43. A gyro motor within the housing 45 drives the gyro wheel 47. An angle piece 49 to which is secured actuating element 37 is rigidly bolted to the outer face of the block 43 in such a manner that actuating element 37 is positioned between the two halves of the contact device. The sole purpose of mounting the anticipating gyro in bearing assembly 38 is to provide freedom of motion about its horizontal or torque axis so that torque forces may be transmitted to the friction damping means in a manner to be explained in more detail later in this specification. It is mentioned now to make known the fact that freedom of angular movement of the gyro about its horizontal or torque axis is limited to such a small degree by the friction damping means that it in no way reacts on the contact device.

With the foregoing in mind and assuming a clockwise rotation of supporting member 9 from its normal or upright position and within its own plane, it is apparent, as has hereinbefore been mentioned, that pendulous member 13, by virtue of its pendulousness and the stabilizing effect thereon by the gyro vertical, will substantially maintain a vertical or earth's center pointing position. The anticipating gyro, by virtue of its mounting on support 9, shares its angular displacement. At the instant angular movement of support 9 begins, the anticipating gyro precesses about its vertical axis in proportion to the velocity of the angular displacement and so moving the actuating element 37 to close a number of the contacts on the left side while opening those on the right, thus providing for an instantaneously high restoring force, that is, force opposing dis-

placement and tending to restore the gun to aimed position. As the angular displacement increases, additional contacts are closed by the actuating element 37 due to its angular displacement with respect to the gyro vertical assembly. When the restoring force reduces the velocity of angular displacement to zero, the angular displacement is greatest and the displacement contact-closing stimulus is a maximum, while the angular velocity is zero and consequently its contact-closing stimulus is zero. The still present displacement stimulus provides for continued application of restoring force in the same sense or direction to the support 9 to move the latter counterclockwise with reversal of angular velocity. As the velocity stimulus is now reversed and subtracts from the displacement stimulus, it opposes the return of support 9 and prevents overtravel or hunting incident to return to a condition of equilibrium. When the angular displacement reaches zero, the displacement stimulus is zero. At this point, however, the counterclockwise angular velocity is maximum, but is opposed by a high opposite force of the anticipating gyro velocity stimulus. With the displacement stimulus at zero and velocity forces opposed, the angular velocity of support 9 is rapidly reduced to zero in a sinusoidal manner. Fig. 6 shows graphically in a slightly exaggerated form, the displacement curve θ and the velocity curve

$$\frac{d\theta}{dt}$$

of support 9. From the above description and Fig. 6, the function of the gyro stabilizer may be summed up as follows. When departing from a position of equilibrium, both velocity and displacement act to deflect contacts in the same sense to provide forces opposing departure from the equilibrium position with the velocity action preceding the displacement action. When away from and approaching the position of equilibrium, displacement deflects contacts in the sense to effect return to the position of equilibrium, but, as velocity reverses at the beginning of the return movement to the equilibrium position, the sense in which it acts on the contacts reverses, that is, the sense is in a direction to oppose return. From the foregoing, it is obvious that the anticipating gyro, by being instantly responsive to the velocity of displacement disturbances of support 9, introduces an anti-hunting effect, thus providing an inherently stable yet highly sensitive control. The gyro vertical's earth's center pointing characteristics are utilized to provide a relative stable mounting for the contact device and to provide a means for measuring the angular displacement of support 9.

In view of the foregoing description, it is readily seen that for the gyro stabilizer assembly to perform its function, it must be angularly displaced in the same amount as the gun; that is, support 9 must be rotated through a corresponding number of degrees as the gun during angular movements of the tank. It must also be adjustably mounted with respect to the gun that it may serve to automatically position the gun in some predetermined elevation. Tank construction practically prohibits the placing of the gyro stabilizer at the trunnion axis of the gun. Previously in said copending application the stabilizing unit was pivoted to the rear of the trunnion axis on the recoil cylinder, but tanks of the type to which this invention applies have the gun mounted to permit high elevation adjustment.

With the stabilizer unit on the recoil cylinder, swinging through an arc of a radius of the unit's displacement from the gun trunnion axis, obstructions were encountered during elevation movements, which restricted full adjustment of the gun. It was, therefore, impossible to mount the gyro stabilizer on the gun. A stationary pivot axis was selected and the gyro stabilizer connected to the gun by means of a parallelogram linkage, the description of which mounting and linkage immediately follows.

A U-shaped bracket member 51 rigidly bolted in an inverted position to an inwardly projecting portion of the forward wall of the tank turret has mounted thereon the hand elevating mechanism indicated generally at 53. To the ends of the downwardly extending portions of U-bracket 51 is bolted a plate 55 which has a rearwardly extending portion 57, to the end of which is pivotally mounted at 58 a member 59.

A worm wheel 61 is pivotally mounted on the axis 58 of member 59 and adjustably fixed to rotate with member 59 by means of worm 63, which is rotatably mounted in a yoke 64 pivotally mounted at 66 and 68 on member 59 in such a position that it will engage the worm wheel 61 and be biased into engagement with said worm wheel by a spring 72 to eliminate backlash. The support 9 (not shown in Fig. 2 for the sake of clearness) of the gyro stabilizer assembly is bolted to the worm wheel so as to rotate with it.

The tank gun is slidably mounted in a frame 65 which is securely bolted in a drum-like member 67 pivoted horizontally on trunnions 7 in an opening in the forward wall of the turret. The center of gravity of the gun assembly, except during recoil from firing, lies in the drum trunnion axis, which axis constitutes the elevation axis of the gun. Attached to the right-hand end of the drum 67 is a gear segment 70 so positioned as to be engaged and rotated by the worm 63 of the hand elevating mechanism 53. A bracket member 71 is mounted on the gear segment 70 by means of bolts 73 extending through the bracket and gear segment into the end of the drum 67, thus securely fastening both bracket 71 and gear segment 70 to the drum 67 so that they may pivot about the trunnion axis 7.

Within the U-shaped portion 75 of bracket member 71 is pivoted at 77 the end 78 of the piston rod 81 extending from the end of a cylinder 83. The other end of cylinder 83 is pivoted at 85 in a U-bracket 81 secured by bolts 89 to the top of tank turret 3. As is more clearly shown in Fig. 2, the end 78 of piston rod 81 is radially positioned with respect to trunnion axis 7 so that forces exerted by the cylinder will rotate the drum 67, which will, in turn, by means of its rigid attachment with the gun 4, move the gun in elevation. One side 81 of the U-shaped portion 75 of bracket 71 is extended, and in its end is pivotally secured at 82 one end of the driving link 93 of the parallelogram linkage. The other end of said link 93 is pivotally secured to member 59 at 95. Pivot 95 is radially disposed with respect to axis 58 of member 59, and pivot 82 radially disposed with respect to trunnion axis 7 in a manner that said pivot axes form a parallelogram; hence, the term "Parallelogram linkage."

Pitching movements of the tank will be shared by the gun by means of its couple with the tank through cylinder 83 during automatic control. The gyro stabilizer unit will be tilted an equal amount about axis 58 by the parallelogram linkage. A flexible driving shaft 97 connects worm

63 to miter gears 99 and 101 which are driven directly from the handwheel 103 of the manual elevating mechanism 53 through shaft 105. Rotation of the handwheel 103 now directly drives worm 63, rotating worm wheel 61 and tilting the gyro stabilizer assembly 5 about axis 58, thus producing an artificial pitching movement.

The worm 63 is connected with the hand-wheel 103 by spiral gears 107 and 109, and is mounted in a housing 111 which is pivotally mounted about the axis of handwheel shaft 105 so that it may be disengaged from the gear segment during automatic elevation control of the gun. The worm 63 may be locked in either engaged or disengaged position with respect to gear segment 70 by means of a locking device 113 so mounted in an extension 115 of U-bracket 51 that locking device 113 may engage holes in the worm housing 111 when the housing is pivotally moved to either of its two positions. The flexible drive shaft 97, in addition to simplifying the connection of worm 63 to handwheel 103, also eliminates the necessity of disengaging the worm 63 from worm wheel 61 when manually elevating the gun through the usual worm 63 and sector 70 because there is freedom for the gyro unit 5 to turn. The tendency of the gyro unit is to remain vertical, however, except for differences in ratio between manual and power elevating control.

Fig. 5 shows in a schematic way the operation of the entire system. A current furnished by a battery or other source of energy 117 is normally equally divided between the right and left-hand portions of resistor 35, since it forms two parallel paths extending, respectively, through actuating coils 119 and 121. Two valves 123 and 125 are interconnected by a common valve actuating element 127 pivoted at 128, both valves being normally open because of normal equal energization of coils 119 and 121 which actuate the poppet or seated-type valves 123 and 125. A motor M drives two simultaneously-operating pumps, for example, those provided by the motor-driven shaft 131 having mounted thereon two screws 133 and 135 of reverse helix which rotate in a bore 137 of pump housing 139. The output is located at the extreme ends of the shaft which is the high-pressure side of the screws, while the intake is located at the center or low-pressure side of the screws, as indicated by the arrows in the respective ports, thus forming, in effect, two separate pumps. Two separate closed paths are indicated by the arrows between each of the pumps and valves 123 and 125. Tapped on the left closed path, that is, the one normally going through valve 123, is a pipe line 141 which is connected to the upper space in a cylinder 83. Similarly tapped on the right closed path, that is, the one normally going through valve 125, is a pipe line 143 which connects to the bottom portion of the chamber of cylinder 83. In operation, the pendulous member 13 and the lower or anticipating gyro, both carried by the supporting plate 9, operate the contacts 33 to apply magnetic forces to the valves 123 and 125 to provide liquid pressures acting on the piston 125 to oppose movement of the gun about the trunnion axis in response to the velocity of such movement and to return the gun to aimed position in the event of departure thereof therefrom. As the supporting plate 9 is connected to move angularly with the gun to move the gyro about an input axis transverse to the spin axis and as the precession or output axis of the gyro is arranged at right angles to the force or input axis and to the spin

axis, from the gyrodynamic relation $T = I_s w_s W$ (where " $I_s w_s$ " is angular momentum of the rotor, "T" is torque about one axis of the pair transverse to the spin axis, and "W" is angular velocity about the other axis of the pair), it follows that angular velocity of the gun about the trunnion axis, and which velocity is applied as input to the gyro, is accompanied by proportional torque of the gyro about the output or precession axis Y-Y; and, due to the scale effect of the centering springs 185 and 187, hereinafter described, the angle of movement about the torque or precession axis Y-Y is a measure of the torque. Therefore, the actuator 37 is moved in proportion to angular velocity of the gun about the mounting or trunnion axis; and, as the contacts require displacement for operation, they are operated by the actuator to provide a pair of voltages whose differential is proportional to the input velocity. As such voltages provide magnetic forces applied to the valves 123 and 125, the liquid pressures are proportional to the voltages; and, as the liquid pressures are applied to opposite faces of the piston 145, the pressure differential, which, from the foregoing, is proportional to angular velocity of the gun about the trunnion axis, is applied as force to the gun, opposing movement thereof. In addition to the gyro operating to minimize angular movement of the gun about the trunnion axis in response to the velocity of such movement, the gravity responsive means, constituted by the pendulous member 13, operates the contacts to control the hydraulic motor means to maintain the support 9 in the vertical or in predetermined relation with respect to the vertical, the gun then being in the aimed or directed position. Should the plate 9 be deviated from this normal positional relation for any reason, then the contacts are operated to control the motor means to move the gun to restore the supporting plate to its normal positional relation. While the piston area at one side of the piston 145 is smaller than that at the other side to the extent of the cross section of the piston rod 81, such area differential may be compensated for, if desired, in a variety of ways, for example, by providing for a compensating differential of forces applied to the valves. A leakage line 147 is connected to the intake line and leads directly through the packing seal through which the piston rod reciprocates, so that as oil leakage occurs past the piston rod, the oil will be able to leak into pipe line 147 instead of forcing its way through the packing seal.

The chamber 149, which encloses the electromagnetically operated valve, constitutes a sump or reservoir. The intake of the pump, in addition to being connected to the leakage line 147, is also connected to the chamber 149.

With the worm gear 69 disengaged from gear sector 70, Fig. 2, rotation of the handwheel through flexible shaft 97 and worm 63 drives worm wheel 61, tilting the gyro stabilizer 5 about axis 58. Assuming for the moment handwheel rotation rotated the gyro unit clockwise, actuating element 37, as has been explained before, will progressively close the contacts 33 at the left-hand side while opening those at the right, decreasing resistance through the left-hand portion of resistor 35 while increasing the resistance through the right-hand portion. It will be seen that more current will flow through coil 121 which will effect counter-clockwise movement of valve actuating element 127 to move the valve 123 in a closing direction and further open valve

125. As a consequence of this, the pressure of the screw 135 of the pump will be directed into the upper chamber of the cylinder 83 to drive the piston 145 down which, by its connection at 5 with the drum 67 in which the gun 1 is rigidly mounted, rotates said drum counterclockwise in a manner to increase the elevation of the gun. Handwheel rotation to tilt the gyro stabilizer counterclockwise will produce an opposite effect on the gun, decreasing the elevation angle. In like manner, pitching of the tank will tilt the gyro stabilizer in the plane of support 9 through cylinder 83 and link 93 of the parallelogram linkage, causing an increase or decrease in the elevation of the gun in a manner to keep the gun trained on a distant target.

During recoil following firing of the gun, excessively large unbalance torques exist which are of a magnitude many times greater than those ordinarily imposed upon the system. Since space limitations and the relatively short periods of recoil, usually of one-half second duration, render impractical the construction of a stabilizing unit sufficiently large to cope with these large unbalances, an additional coil 150 has been added to the valve operator of valve 123 and is connected in series with the battery 117. A recoil switch 152 of the micro-type maintained open by the gun breech is closed during recoil when the gun breech recedes therefrom, energizing the valve coil, closing valve 125, thus developing the needed pressure to support the large unbalance. A ball or check valve 153 is installed in the pump output which leads to the bottom portion of the cylinder chamber to prevent the back pressure from entering the pump when it is in excess of the peak delivery of the pump. The hydraulic pressures in the stabilizer cylinder 83 are controlled by their respective valve currents. As the sensitivity regulator resistor 155 is adjusted to increase the change in valve currents the stabilizer accuracy is increased.

The friction damping means as used in our invention is a contribution described and claimed in a copending application of C. R. Hanna, S. J. Mikina and L. B. Lynn, Serial No. 412,612, filed September 27, 1941, entitled Electric traverse for turrets. Precessional movements of the anticipating gyro were previously damped with oil dampers described and claimed in a copending application of C. R. Hanna and L. B. Lynn, Serial No. 366,877, filed November 23, 1940, entitled Gun stabilizers, but their performance varies with changes in oil viscosity due in turn to changes in temperature. Since it is highly desirable to have a consistent gyro performance in response to differential movements, the oil damper is not always entirely satisfactory. The friction damper represents an improvement over the oil damper in both uniformity of operation and simplicity of design and adjustment. Referring to the drawings, we have in Fig. 3 a perspective showing of the anticipating gyro of the gyro stabilizer assembly 5. Fig. 4 is a section taken vertically 60 through the bearing axis showing the pivotal mounting of U-bracket 41. Centrally secured to the base of U-member 41 is a stub shaft 157, which shaft is positioned within the inner races of ball bearings 159 and 161 axially spaced along shaft 157 at its root and extremity, respectively, by means of annular grooves 163 and 165 turned within the ends of bearing housing 167. By means of flange 169 and a portion of the housing 167 extending through a hole in support 9, the housing is positioned and securely bolted to

said support. A circular plate 171 of diameter slightly larger than the stub shaft 157 is fastened to the end of said shaft in a manner to bear against the inner race of ball bearing 161, thereby preventing axial travel of shaft 157. A cover plate 173 is pressed into the end of the annular opening 168. Pivotally mounted about a vertical axis in bearings in U-bracket 41 is a block 43, in the bore of which is securely clamped the motor housing 45 of the anticipating gyro. The L-shaped torque transmitting arm 175 (see Fig. 3) is so positioned and secured on block 43 that its frictionally engaged end 177 lies between friction shoes 179 and 181 adjustably mounted on set screws in a U-bracket 183 rigidly secured to support 8. It is necessary, when mounting the anticipating gyro in block 43, that the center of gravity of said gyro including L-shaped torque arm shall be in the intersection of the vertical or y axis and the horizontal or x axis so that force or static unbalance may not be transmitted by the torque arm to the friction damper. Friction forces therein formed for true damping of precessional movements must be proportional to the velocity of angular displacement of support 8 within its own plane, which is a displacement velocity about the x axis of the gyro. Any movement of the gyro about its horizontal or x axis causes the gyro to precess about its vertical or y axis against the stiff restraining springs 185 and 187. Torque about the vertical axis is proportional to velocity about the horizontal axis and deflects the restraining springs 185 and 187 a proportional amount. Precessional velocity about the vertical axis produces a reaction torque about the horizontal axis, and the torque arm 175 and friction shoes 179 and 181 therefore engage with a normal force proportional to this torque. But during precession about the vertical axis, the portion 177 of arm 175 slides with respect to the friction shoes, with the result that, as the friction developed is proportional to the applied or reaction torque, that is, torque about the x axis due to angular displacement, which, in turn, is proportional to the precessional velocity about the vertical axis, friction torque is developed proportional to the precessional velocity which produced the reaction torque. Thus, damping is proportional both to precessional velocity and reaction torque. The damping thus obtained depends upon the radius at which the friction forces act with respect to torque, upon the radius at which the friction forces act with respect to precession, and upon choosing materials having the proper coefficients of friction. The friction shoes are so adjusted to allow clearance of member 177 of arm 175 between their faces; while there is slight lost motion between the shoes and the arm, it is of such a small quantity that it in no way effects the stimulus of actuating element 37. The outer ends of restraining springs 185 and 187 are stationarily mounted to adjustment screws 189 and 191 threaded and locked in the extremities of U-bracket 183 in turn fastened to the bottom of U-bracket 41. Angle piece 49 at its bottom is reduced in size and bent inwardly. The inner ends of springs 185 and 187 are secured in holes in the reduced portion of said angle piece. From this construction, it is obvious that the springs provide a positive return of the anticipating gyro to its normal position; their stiffness is also adjusted to regulate precession angles within limits as required by the control system and which stiffness at the same time prevents the gyro from responding to

vibrations or disturbances below those of a pre-determined frequency, for instance, turning movements of the turret. Rotation of the gyro about its vertical or y axis is limited by set screws 195 and 197 threaded into the forked end of the bottom portion of U-bracket 41, thereby preventing excessive or damaging deflections of the contacts.

We are, of course, aware that others, particularly after having had the benefit of the teachings of our invention, may devise other devices embodying our invention, and, we, therefore, do not wish to be limited to the specific showings made in the drawings and the descriptive disclosure hereinbefore made, but wish to be limited only by the scope of the appended claims.

We claim as our invention:

1. In combination, a movable support provided with a turret, a gun pivotally mounted in the turret, actuating means connecting the gun to the turret and operative to move the gun angularly about its mounting axis, mechanism responsive to angular movement of the gun about its mounting axis to control the actuating means for regulating the angular position of the gun with respect to such axis, and apparatus providing for mounting of said mechanism in the turret so as not to interfere with angular movement of the gun about its mounting axis; said apparatus comprising a manually-operable control element, means for transmitting angular movements from said control element to said mechanism to render the latter effective to move the gun angularly about its mounting axis, means for transmitting angular movements of said control element directly to the gun, and means providing for connection and disconnection of the last-named means.

2. In combination, a movable support provided with a turret, a gun pivotally mounted in the turret, actuating means connecting the gun to the turret and operative to move the gun angularly about its mounting axis, mechanism responsive to angular movement of the gun about its mounting axis to control the actuating means for regulating the angular position of the gun with respect to such axis, and apparatus providing for mounting of said mechanism in the turret so as not to interfere with angular movement of the gun about its mounting axis; said apparatus comprising a bracket structure attached to the turret, an arm pivotally mounted on the bracket structure, a support for the mechanism and pivotally mounted on the bracket structure in coaxial relation with the arm, parallel-motion linkage means connecting the gun and the arm, irreversible gearing connecting the arm and the support and including a driving gear rotatably carried by the arm, a manually-rotatable control element carried by the bracket structure, and means for transmitting motion from the control element to the driving gear.

3. Apparatus according to claim 2 wherein the means for transmitting motion from the control element to the driving gear is comprised by a flexible shaft.

4. In combination, a movable support provided with a turret, a gun pivotally mounted in the turret, a gear element connected to the gun in coaxial relation with respect to the mounting axis, actuating means connecting the gun to the turret and operative to move the gun angularly about its mounting axis, mechanism responsive to angular movement of the gun about its mounting axis to control the actuating means for regu-

lating the angular position of the gun about such axis, and apparatus providing for mounting of said mechanism in the turret so as not to interfere with angular movement of the gun about its mounting axis; said apparatus comprising a bracket structure attached to the turret, an arm pivotally mounted on the bracket structure, a support for the mechanism and pivotally mounted on the bracket structure in coaxial relation with the arm, parallel-motion linkage means connecting the gun and the arm, irreversible gearing connecting the arm and the support and including a driving gear rotatably carried by the arm, a manually-operable rotary shaft carried by the bracket structure, a housing pivoted for 15 angular movement about the axis of said shaft,

5 a driving gear rotatably carried by the housing, means including constantly meshed gears connecting the control shaft and the driving gear, means for transmitting motion from the control shaft to the first-mentioned driving gear, and means for positioning the housing with the second-mentioned driving gear in meshed or de-meshed relation with respect to said gear element.

10 5. Apparatus according to claim 4 wherein the means for transmitting motion from the control shaft to the first-mentioned driving gear is comprised by a flexible shaft.
